UNITED STATES PATENT OFFICE.

ROLLIN L. COONS, OF COUDERSPORT, PENNSYLVANIA.

COMBINED SECTION FOLDER AND PRESS, AND FOUNDATION FASTENER FOR HONEY-COMBS.

Application filed November 6, 1926. Serial No. 146,636.

My invention relates to new and useful improvements in a combined section folder and press, and foundation fastener for honey combs, and has for an object to combine in one machine a honey comb section folder, a press therefor, and a foundation fastener which will be inexpensive although strong and durable and efficient in operation.

Usually a honey comb section is folded manually, then placed in a manually operated press requiring a number of operations to properly align the serrated ends of the section and force them into interlocking engagement, and the foundation afterwards heated and manually forced into engagement with a side of the section until said foundation adheres to the section.

One of the objects of the present invention is to overcome the disadvantages set forth above or eliminate the majority of the manual operations by making the machine semi-automatic and carrying out all the operations to produce the complete section and attached foundation.

Another object of the invention is to so arrange the parts that the section receiving chamber is in an inclined position making it convenient for the operator to drop the foundation into place and increasing the visibility of the operations.

A further object of my invention is to provide for projecting the hot plate into the section through the operations of the folding wing, and to trip said hot plate by the actuation of the operating lever as the section end closure is folded and locked.

A still further object of the invention is to provide a forming block on the folding wing about which block the section is partly folded, said block also acting as a positioning device or rest for the foundation.

Other objects are to provide means to guide the section walls into proper alignment; to draw parts together after the manner of a clamp; and to provide for adjusting a number of the elements of the machine.

With these and other ends in view, this invention consists in the details of construction and combination of elements hereinafter set forth and then specifically designated by the claims.

In order that those skilled in the art to which this invention appertains, may understand how to make and use the same, I will describe its construction in detail, referring

by numerals to the accompanying drawings forming a part of this application, in which:

Fig. 1, is a side elevation of the combined section folder and press and foundation fastener constructed according to my invention with the parts illustrated in the positions assumed when ready to receive the section.

Fig. 2, is an enlarged fragmentary side elevation with parts broken away and illustrating the first movement of the machine.

Fig. 3, is a rear view of Fig. 1.

Fig. 4, is a front elevation thereof.

Fig. 5, is a top plan view of the machine in the position illustrated in Figs. 1 and 4.

Fig. 6, is also a top plan view at the end of the final operation.

Fig. 7, is a perspective view of the finished product made by the use of this machine.

Fig. 8 is an enlarged fragmentary front elevation of the upper end of the member 17 with a portion broken away and shown in section to illustrate the adjustability of the pin which coacts with other elements to draw the side members toward each other.

In carrying out my invention as herein embodied, 15 represents a base of suitable shape and dimensions which may be secured directly to a supporting surface, such as the floor of a building, or it may be provided with a transverse foot piece 16 at its forward end on which the operator's feet may be placed to prevent the machine from tipping or moving about while in use when not permanently secured. To the rear end of the base at the sides thereof are secured the side or frame members 17 and 18 which are inclined forwardly and upwardly, or are arranged obliquely to the base of the machine so that the upper ends are substantially in line with the eyes of the operator sitting in front of the machine. These side pieces are adjustable relative to each other by means of a tie rod 19 having right and left hand threads and screwed into said side pieces intermediate their ends at a point above their middle.

In the side pieces is mounted a bolt 20 or axle for the operating lever 21 which is mounted between washers on the projecting ends of said bolt or axle; and said bolt or axle passes through a longitudinal slot 22 in a slide 23 mounted on the outside of the side frame 17, and in addition to being guided through the medium of its slot and the bolt or axle 20 oppositely disposed guides 24 are secured to the side member 17. There are two

guides 24 mounted on opposite faces of the side pieces 17 and provided with right angled flanges which register with the guide-way 25 formed on opposite faces of the slide 23.

5 It may be well to mention at this point that the frame or side members are further supported on the base by braces 27 and 28 one of which is connected with each of the side pieces 17 and 18 respectively, and to the base.

10 To the lower portion of the slide 23 is pivoted one end of the connecting rod 29, as at 30, while the other end of said connecting rod is pivoted to the leg 31 of the operating lever, as at 32, and the distance between the 15 points 20, 32 and 30, Fig. 1, is such that when the leg of the operating lever and the connecting rod 29 are in endwise alignment, the slide 23 is in its extreme lower position.

One of the functions of the slide is to operate 20 the section end folder and locker 33 through the medium of the pitman 34, one end of which is pivoted at 35 to the slide 23, while the other end is pivoted at 36 to said section end folder and locker. Said section end folder and locker 33 is hinged as at 37 to the upper end of the side or frame member 18, and is adapted to bridge the space between the upper ends of both of the side or frame members.

30 During the operations which bring said folder and locker 33 into the position across the ends of the side members, the cam pin 38 having a beveled inner surface 39 engages with the bearing pin 40 projecting from the outer side face at the upper end of the side or frame member 17, and said bearing pin is adjustable in order that any lost motion or wear on the parts may be taken up from time to time, or so that the upper ends of the 35 side or frame members may be drawn toward each other, more or less, according to the size of any set of sections, and in order that the slide 23 may pass over the bearing pin, the upper end of said slide may be grooved, as indicated at 41.

Projecting downwardly from opposite sides of the folder and locker 33 at the free end of the latter are side panels 42, the inner ends of which are beveled, as at 43, in order to assist in aligning parts of the section, as will be more fully later described.

On the rear edges of the side or frame members near their upper ends is mounted a section stop 44, the same having one end permanently secured to one of the side members by screws 45 or their equivalent, while the other end is connected with the other side member by screws 46 which pass through slots 47 in the section stop, thereby permitting the side members to be drawn toward each other by the cam pin 38 when engaging the bearing pin 40, as previously described. On the inner surface of the section stop are secured comb foundation guides 48 which are adjustable by means of the adjusting screws 49, having

threaded engagement with the section stop and impinging against the inner surfaces of the comb guides, so as to force them away from the section stop, and when said screws are backed out, said guides will remain toward the section stop through the inherent resiliency of the metal, from which said guides are formed.

On the inner surface of each side or frame member is mounted the section holder 50 by 75 means of a bolt 51 and its associated nut 52, or other equivalent fastening means, the said bolt passing through a slot 53 in the holder to permit of adjustment of the latter. It is necessary to make the holders adjustable in 80 order that any variation in the sizes of different sets of sections may be compensated for and in order that both holders can be made to align with each other.

To the forward faces of the side or frame members are hinged the lower ends of the limbs 54 of the folding wing 55, and as herein illustrated, the hinges 56 beside being attached to the limbs of the folding wing are also attached to blocks 57, which may be mounted on the front faces of the side members or may be projecting parts thereof. The folding wing carries a forming block 58 which is adapted to be projected into the space between the side or frame members above the section holders 50, and which space, I term, the section receiving chamber, for convenience of description. The upper end of the forming block is preferably beveled, as at 59, in order that the entrance to the receiving chamber may be as wide as possible, while below the folding block and spaced therefrom is a folding jig 60, and into the space between said folding jig and the forming block is projected the hot plate to be 100 presently described. The folding wing is limited in its downward or opening movement by a latch 61 pivoted to one side of said wing and cooperating with a pin 62 on one 105 of the side or frame members.

Projecting from one of the limbs of the folding wing beyond its hinge point and longitudinally thereof is a tail piece 63 carrying a pin 64 for cooperation with the indent of the catch 65, having one end pivoted as at 66 to the hot plate arm 67, which is pivoted intermediate its ends as at 68 to one of the frame or side members, and, as will be noted, the catch is pivoted above the pivoting point of said hot plate arm.

On the upper end of the hot plate arm is adjustably mounted a bracket 69 by means of a screw 70 or its equivalent passing through the hot plate arm and through a slot in said bracket. The bracket is of right angle shape, as plainly seen in Fig. 3, and is provided with a slot 71 in its horizontal arm for the reception of a bolt 72 or other suitable fastening means, which bolt also passes through a slot 73 in the shank 74 of the hot 120 plate arm.

plate 75, thus providing for adjustment of the hot plate forward or backward and side-
wise, and the bracket itself being adjusted
upon the hot plate arm, it may be moved up
5 or down on said arm, and rotated so as to
properly position the hot plate for entrance
into the space between the forming block
and jig.

The hot plate is normally held in its for-
ward position or the position illustrated in
Fig. 1 by means of a spring 76, one end of
which is attached to the anchor 77 as the
stationary element, said anchor preferably
being formed from stiff wire and secured to
15 one of the side or frame members, while the
other end of said spring is suitably attached
to the hot plate arm below its pivoting point
68, and the movement of said arm by said
spring is limited through the medium of a
20 stop 78 carried by the lower free end of said
arm and coacting with the brace 27.

In order to trip the catch 65 so as to disen-
gage it from the pin 64, a trigger 79 is pivoted
intermediate its ends at 80, and said ends are
25 separated so that looking at the side of the
machine the trigger is substantially an in-
verted V with one end turned inward to
underlie the nose of the catch 65 and the other
end turned downward for coaction with the
30 trigger operating cam 81, the latter being
fixed on the slide and having a lower beveled
or cam end 82, which will ride under the out-
wardly projecting end of the trigger and
actuate it to raise the nose of the catch,
35 thereby disengaging the latter from the pin
64, and permitting the spring 76 to act upon
the hot plate arm.

In order that the hot plate may be properly
heated a suitable heating device 83, herein
40 shown as a lamp resting upon a platform 84
is provided with a standard 85 having a lon-
gitudinal slot 86 therein whereby said plat-
form is adjustably mounted through the me-
dium of a bolt 87 or its equivalent passing
45 through one of the side or frame members
and through the longitudinal slot in the
standard 85.

In order to make further adjustments for
positioning the comb foundation, secondary
50 guide fingers 88 may have their upper ends
secured to the upper end of the forming block
with their lower ends free so that they may
be moved away from the forming block by
means of adjusting screws 89, while their in-
55 herent resiliency will cause them to return
toward the forming block, as the screws 89
are backed out.

In actual practice, the operation of the
device is as follows:

60 One of the transversely grooved strips is
positioned by the operator across the fold-
ing wing below the jig with that portion of
the strip which will become an end 90, Fig.
2, of the section against said jig, thereby per-
65 mitting the side members 91 of the section

to be folded inward against the forming
block 58. When this has been done, the fold-
ing wing is elevated or swung on its hinges
70 until it enters the section receiving chamber
17 and 18 with the forming block inside of the
section thus formed, and at the end of the
movement of the folding wing the sides of
the section will be tightly held between the
75 section stop and said folding wing.

The movement of the folding wing into
the closed position as illustrated in Fig. 2
causes the upper end of the hot plate arm
67 to be drawn inward through the medium
of the catch 65 and against the action of the
80 spring 76 so that the hot plate 75 is projected
into the space between the lower end of the
forming block 58 and jig 60, and as said hot
plate overlies the heating device 83 during
85 its period of rest it is maintained at a tem-
perature sufficient to melt the wax of the
foundation 92, which is dropped into the re-
ceiving chamber, while the folding wing is
90 in the closed position, and therefore one edge
of the foundation is softened and melted.

After the foundation has been placed
within the partially folded section lying
within the receiving chamber, the operating
lever is actuated causing the slide 23 to be
moved downward, thus carrying the cam 95
81 back of the outwardly projecting end of
the trigger 79, so as to lift the opposite end
and trip the catch 65, which will permit the
spring 76 to function, and draw the hot
100 plate outward. Upon withdrawal of the
hot plate from the receiving chamber, the
foundation 92 resting thereon will drop down
on to the end wall 90 of the honey comb sec-
tion to which the foundation will adhere.
The foundation will be properly positioned
105 in the center of the section due to the position
of the forming block and the adjustment of
the guides 48, or when guides 88 are used
then the foundation is positioned due to the
adjustments of both sets of guides 48 and 88. 110

The continued movement of the operating
handle swings the section end folder and
locker 33 downward through the medium of
the pitman 34 thus folding in the section end
93, and if for any reason, such as a miscut in
115 the grooves of the section strip, said section
end 93 might not properly align with the co-
acting section side, said section end will be
moved into proper aligning position by the
beveled ends of the panels 42 which move
120 over the section end 93, as the folder and
locker 33 is closed due to the difference in
positions of the hinge of the member 33 and
the folding line of the section end 93.

When the folder and locker 33 has reached
125 its limit of movement the serrations of the
section end 93 will be pressed into interlock-
ing engagement with similar serrations on the
coacting section side and at the same time
the cam pin 38 engaging the bearing pin 40 130

will cause the frame side members 17 and 18 to be drawn together at their upper ends and thus force the serrated section side into firm engagement with the serrated section end 93.

During the final operations the panels 42 pass over one of the frame side members of the machine and over a portion of the folded section as well as over a part of the folding 10 wing 55 so that the latter will not open until the operating handle is reversed.

When the operating handle is reversed the folding wing will be released and will drop by gravity into its open position where it is 15 held by the latch 61, then the frame side members of the machine are released and the folder and locker finally moved into its raised position, thus releasing the folded section with the attached foundation so that it may 20 be readily removed from the receiving chamber.

Of course I do not wish to be limited to the exact details of construction as herein shown as these may be varied within the limits of 25 the appended claims without departing from the spirit of my invention.

Having thus fully described my invention what I claim as new and useful is:

1. A section folder, press and foundation 30 fastener, comprising a frame the upper portion of which forms part of a section receiving chamber, a folding wing hinged to the frame, a forming block on the wing and about which a section is partially folded, a 35 hot plate actuated by the folding wing for projection into the chamber, a section end folder, and a mechanism to trip the hot plate and simultaneously actuate the section end 40 folder for moving the serrated portions of a section into locking position.

2. The structure set forth in claim 1 wherein in the receiving chamber is inclined downwardly and rearwardly.

3. In a device of the character stated, inclined side members, means on the inner surfaces of said members to hold a partially folded section, means projectible into the space between the side members and about which the section is partially folded, means 45 operable in one direction by a spring, and in the opposite direction by the second named means for projection into the partially folded section to melt an edge of a wax foundation placed in the partially folded section, means to fold the remaining section end and press 50 it into interlocking engagement with a coacting section side, and a mechanism to operate the last mentioned means and simultaneously trip the foundation heating means at the beginning of the operations of said mechanism.

4. The structure set forth in claim 3 in connection with means on the final section end folder and co-operating with means on one of the side members to draw said side members toward each other.

5. In a device of this character, the combination with a section receiving chamber, means to close one side of said chamber and means folding and pressing into place the finally foldable end of the section in the chamber, of side panels on said folding means to align said section end with the section sides. 70

6. The structure set forth in claim 5 in which the inner ends of the panels are beveled.

7. The combination with a section folding 75 machine including frame side members between which is located a section receiving chamber, a member hinged at one end to one of the frame side members and adapted, when swung across the chamber, to fold the finally 80 foldable end of a section in the chamber, and means to actuate the hinged member, of side panels at the free end of the hinged member of less length than and projecting beyond the inner face of said member, said panels having 85 beveled inner ends to align the finally foldable section with a coacting section side.

8. The structure set forth in claim 7, in combination with a cam pin on the free end of the hinged member, and a bearing pin on the frame side member opposite the one on which the hinged member is mounted, the cam pin coacting with the bearing pin to draw the frame side members toward each other in order to properly position the section sides. 95

9. In a machine of the character stated, a frame provided with a section receiving chamber, a member hinged to a side of the frame and coacting with the other side thereof and adapted to fold the finally foldable 100 serrated section end when moved across the chamber, bearing means on said other side of the frame, means carried by the hinged member and coacting with said bearing means to draw said frame sides toward each other and thereby assist to force a serrated section side 105 into interlocking engagement with the serrated section end, and means to operate the hinged member.

10. The structure in claim 9 wherein the bearing means on said other side of the frame and coacting with the means on the hinged member, is adjustable to compensate for lost motion and wear on the parts.

11. A machine of the class stated, including 110 frame side members providing a section receiving chamber therebetween, a section stop positioned across the rear of said side members, guides carried by said stop and projecting into the chamber, means to adjust the positions of said guides, a folding wing hinged to the forward edges of the frame side members, a forming block on the wing, a jig on the wing in spaced relation to the block, said block and jig being projectible into the section receiving chamber with a section partially folded thereabout, an oscillating hot plate spring actuated in one direction, means to heat said plate, mechanism to transmit motion from the wing to the hot plate whereby the 120 125 130

latter is projected into the chamber as the wing is closed on said chamber, said plate extending into the space between the block and jig with the spring under tension, and means 5 to trip the hot plate so as to release it from the wing and permit the spring to act on the hot plate.

12. The structure set forth in claim 11, in combination with a member hinged to one of 10 the frame side members and coacting with the other of said side members, and means to operate said hinged member and actuate the trip means for releasing the hot plate from the wing.

13. A combined section folder and press and foundation fastener for honey combs comprising inwardly inclined frame side members providing a section receiving chamber therebetween at their upper ends, holders, means to adjustably mount said holders on the inner surfaces of the frame members, a section stop disposed across the rear edges of the frame members, a folding wing hinged to the forward edges of the frame members 25 and manually operable to close the front of the receiving chamber, forming means on the wing about which a section is partially foldable prior to insertion in the receiving chamber due to swinging the wing toward said 30 chamber, a hot plate, spring actuated in one direction, means connected with the wing to move the hot plate against the action of the spring for projecting it into the receiving chamber, means to heat said hot plate, means 35 to fold the finally foldable section end, means to operate the last mentioned means and means connected with the operating means to trip the hot plate and permit the spring to withdraw said hot plate while leaving the 40 wing in the raised position, said hot plate melting an edge of a wax foundation inserted in the partially folded section whereby said foundation will adhere to a wall of the section upon dropping thereon, as the hot plate is 45 withdrawn.

14. The structure set forth in claim 13 in combination with guides adjustably mounted on the section stop and other guides adjustably mounted on the means carried by the 50 wing, and about which the section is partially foldable.

15. In a machine of the class described, a section receiving chamber, a folding wing hinged adjacent said chamber, means on said wing about which a section is partially folded, 55 said wing being manually operable to project the partially folded section into the chamber, an oscillating hot plate, motion transmitting means to oscillate the hot plate in one direction, a spring tending to move the hot plate in the opposite direction, means to heat said hot plate, a slide, means to operate said slide, means associated with said slide to trip the hot plate, means to fold the finally foldable section end, and means to transmit motion 60 from the slide to the means which folds the finally foldable section end.

16. The structure set forth in claim 15 in combination with guides in the chamber to guide a wax foundation into a desired location relative to the section in the chamber, and means to adjust said guides. 70

17. In a machine of the character described, a frame, a folding wing hinged to said frame, an oscillating hot plate pivoted to the frame, 75 a spring tending to hold the hot plate in an inoperative position, a catch pivoted to the oscillating hot plate, an extension carried by the wing and projecting beyond its hinging point, a pin carried by said extension for co-operation with the catch whereby an inward swinging movement of the wing will transmit an inward swinging movement to the oscillating hot plate, a pivoted trigger associated with the catch, a slide, a cam on said slide to actuate the trigger for disengaging the catch from its pin and permitting the hot plate to be moved to its inoperative position through the medium of the spring while the wing remains in its inward position, means to actuate 80 the slide, a section end folder, and means for transmitting motion from the slide to said section end folder.

18. The structure set forth in claim 17 wherein the oscillating hot plate includes an 95 arm, a bracket adjustably mounted on the upper end of said arm, and the hot plate proper adjustably connected with the bracket.

In testimony whereof, I have hereunto affixed my signature.

ROLLIN L. COONS.
